ASH TRAY OR SIMILAR ARTICLE

Lawrence M. Furey, Warwick, Va.

Application May 7, 1957, Serial No. 46,039

Term of patent 14 years

(Cl. D85—2)

(Granted under Title 35, U. S. Code (1952), sec. 266)

The invention described herein may be manufactured and used by or for the Government for governmental purposes without the payment to me of any royalty thereon.

I claim:

The ornamental design for an ash tray or similar article, as shown.
